Primary Examiner—Philip S. Hyder*Attorney, Agent, or Firm*—Fitch, Even, Tabin & Flannery[57] **CLAIM**

The ornamental design for a tool box, as shown and described.

DESCRIPTION

FIG. 1 is a perspective view of a tool box showing a first embodiment of my design;

FIG. 2 is a perspective view of a tool box showing a second embodiment of my design;

FIG. 3 is a perspective view of a tool box showing a third embodiment of my design; and,

FIG. 4 is a perspective view showing the tool box with the cover in a raised position, said view being identical for all three embodiments.

The appearance of the unshown surfaces of the tool box form no part of the claimed design.
